TOOTHPICK EJECTOR

Filed Aug. 3, 1931

FIG. 1

FIG. 2

FIG. 4

FIG. 3

Inventor
H. Altinger

By his Attorney J. Ledermann

UNITED STATES PATENT OFFICE

HANS ALTINGER, OF NEW YORK, N. Y.

TOOTHPICK EJECTOR

Application filed August 3, 1931. Serial No. 554,633.

The main object of this invention is to provide a device which ejects a single tooth pick every time a knob is rotated.

Another object of the invention is to provide a casing in which a channel drum is rotatable, the channel drum picking up a tooth pick every time the same is rotated, and delivering said tooth pick to a chute which utilizes a tray.

10 The above and other objects will become apparent in the description below in which characters of reference refer to like-named parts in the drawing.

Referring briefly to the drawing, Figure 1 is a longitudinal, sectional, elevational view of the tooth pick ejector, showing the barrel in loaded condition.

Figure 2 is a front elevational view of Figure 1.

20 Figure 3 is a top plan view of Figure 1, showing the cover in open position.

Figure 4 is an enlarged, sectional, elevational view through the barrel and a portion of the chute wall, showing the evictor tongue 25 in active position.

Referring in detail to the drawing, the numeral 10 indicates a base plate from which a pedestal 11 rises. This pedestal supports the bottom 12 of the rear casing wall 13 of the device. Extending from the edge of the bottom 12 are a pair of ears 14 and 15 which are deformed to provide saddles 16 into which tooth picks are precipitated by the mechanism. The front wall 17 of the casing is separated 35 from the rear wall and at its lower end is curved inwardly as indicated by the numeral 18, thereby providing a tapering passageway 19 between the periphery 20 of the barrel 21 and the wall 17. The barrel is provided with 40 studs 22 at opposite ends which are journaled in suitable openings formed in the end walls 23 and 24 of the casing. One of these studs 22 is elongated to provide a means of mounting for a knurled thumb nut 25. At 45 one position on the periphery 20 of the barrel 21 a longitudinal channel 26 is formed and extends parallel to the axis of said barrel. This channel enters the barrel in inclined relation thereto and is adapted to receive a tooth 50 pick 27 as said channel passes beneath the

tooth picks in the tooth pick hopper 28 formed between curved chute walls 29 and 30 which are secured permanently and rigidly to the walls 17 and 13 respectively. A conveyor ramp 31 extends from the wall 29 in the chamber 28 and is adapted to pack and distribute these tooth picks 27 at the rear position in the chamber 28. Continuing from the lower edge of the chute wall 29 beneath the ramp 31 are a pair of deformed tongues 32 which extend into and are received in annular raceways 33 formed at spaced apart positions on the periphery 21. As more than one tooth pick may enter the channel 26 because of its depth, these tongues are adapted to evict all 60 but a single tooth pick from said channel by urging all but the one tooth pick out of the channel 26. Within one of the raceways 33 a detent 34 is provided. This detent is adapted to receive the curved end of a resilient 65 break finger 35.

The device in operation is adapted through a single rotation of the knob 25 to expel a single tooth pick upon the saddle 16 from which the operator of the device may readily remove the same by inserting the tips of the fingers between the tongues 14 and 15. The resilient break finger 35 when tripping into the detent 34 indicates that the channel 26 in the barrel 21 is loaded with a tooth pick and the evictor tongues 32 have removed all 80 but a single tooth pick from the channel or for preventing the falling into the channel of more than one tooth pick. By rotating the knob 25 in a clock-wise direction the barrel is 85 arcuately turned and with this turn the channel 26 is moved from the loading position beneath the tooth picks 27 to a position where said channel assumes a downwardly inclined angle after which the tooth pick contained in said channel is precipitated into the chute 19 out of which it falls into the saddle 16 of the ears 14 and 15. To fill the chamber 28 with tooth picks the door 36 is opened by swinging 90 the same about the hinge sleeves 37.

It is to be noted that certain changes in form and construction may be made without departing from the spirit and scope of the invention.

I claim:

A device of the class described comprising an upright casing substantially rectangular in cross-section, a cylindrical barrel rotatably mounted in the lower part of said casing, inwardly inclined walls on opposite sides of said casing integral with said casing and extending convergently toward the periphery of said barrel to form a hopper above said barrel, the lower edges of said walls being parallel to the axis of said barrel, the lower edge of one of said walls substantially contacting with said periphery on a line to one side of the axis of said barrel, the lower edge of the other of said walls lying at a distance from said periphery directly above said axis to provide a gap between said periphery and said second-named lower edge, an outlet in said casing beneath said barrel, said barrel having a surface channel extending parallel to the axis of the barrel, said channel extending into the barrel at an angle to a radial line drawn between the axis of the barrel and the mouth of said channel, a peripheral groove on either side of said barrel extending entirely around said barrel, resilient tongues extending from said casing beneath said second-named lower edge and riding in said grooves, the ends of said tongues being arcuately looped, the convex sides of said loops partly entering said channel as said ends ride by said channel during rotation of said barrel, said looped ends on said tongues being yieldably movable between said periphery and said second-named lower edge as a limit stop.

In testimony whereof I affix my signature.
HANS ALTINGER.
